UNITED STATES PATENT OFFICE

144,017

DESIGN FOR A CEDAR CHEST OR SIMILAR ARTICLE

Earl E. Abbott, Science Hill, Ky.

Application May 16, 1945, Serial No. 119,566

Term of patent 7 years

(Cl. D33—19)

To all whom it may concern:

Be it known that I, Earl E. Abbott, a citizen of the United States, residing at Science Hill, in the county of Pulaski and State of Kentucky, have invented a new, original, and ornamental Design for a Cedar Chest or Similar Article, of which the following is a specification, reference being had to the accompanying drawing, forming part thereof.

The figure is a perspective view of a cedar chest or similar article, showing my new design. The opposite end and the rear portion are substantially like the end section and front section shown in the figure.

I claim:

The ornamental design for a cedar chest or similar article, as shown and described.

EARL E. ABBOTT.
